C. J. LOUIS

ATTACHMENT FOR RESHAPING TUBULAR MEMBERS

Filed Jan. 20, 1923

UNITED STATES PATENT OFFICE.

CHARLES J. LOUIS, OF ST. LOUIS, MISSOURI, ASSIGNOR OF TWO-THIRDS TO N. T. ERLINGER, OF EAST ST. LOUIS, ILLINOIS.

ATTACHMENT FOR RESHAPING TUBULAR MEMBERS.

Application filed January 20, 1923. Serial No. 613,962.

This invention relates to devices such as are used in the manufacture of tubular members made from a fibrous material, the primary object thereof being for the purpose of 5 providing an improved attachment for reshaping tubular fibrous members.

Another object of the invention is to provide a different method than heretofore used in the manufacture of tubular members.

10 A further object of the invention is in providing an attachment to a device for making tubular members whereby the members are formed into a different shape than that in which they were previously made.

15 A still further object of the invention is in providing an attachment whereby tubular members are swaged into a different contour.

Other and further objects will appear in the specification and be specifically pointed 20 out in the appended claims, reference being had to the accompanying drawings, exemplifying the invention, and in which:

Figure 1 is a plan view of a machine used in the manufacture of fibrous tubular members showing this improved attachment in 25 section and applied thereto.

Figure 2 is an enlarged vertical section taken on the line II—II of Fig. 1.

Figure 3 is an enlarged vertical section 30 taken on the line III—III of Fig. 1.

Figure 4 is an enlarged perspective view of the swaging tool used in connection with this improved attachment.

Referring by numerals to the accompanying drawings, 1 designates a supporting frame of a machine and longitudinally supported thereabove is a mandrel 2 which is rigidly supported at one end in a rest 3 by the set screws 4.

40 This improved attachment designated as 5 is adapted to support the opposite end of the mandrel 2, in which a turned down portion 6 is extended from the end of the mandrel adjacent the attachment 5, said extension being supported in the swaging tool 7 which forms 5 part of the attachment 5.

This improved attachment is comprised of a pair of vertically arranged plates 8 and 9 each having respective hub-like portions 10 and 11 which abut, said hub-like portions providing a centrally arranged opening 12 through which the swaging tool 7 is projected.

Passing through the abutting hubs 10 and 55 11 of the respective plates 8 and 9 are a series

of screws 13 which are used for holding said hubs in abutment with one another, and provided by said hubs between the plates 8 and 9 is an annular groove 14, and mounted within said groove is a supporting collar 15 which encircles the outer peripheries of the hubs 10 and 11, and arranged between said hubs and the inner surface of the collar 15 are a series of roller bearings 16.

The collar 15 is adapted to support the attachment 5 from a bracket 17 which is secured to the supporting frame 1, there being a pin 18 projecting from said bracket to said collar.

Formed on one of the faces of the plate 8 are a pair of spaced apart guiding ledges 19 and arranged between said ledges are a pair of slidable blocks 20, each block being disposed on a respective side of the opening 12 through which the swaging tool 7 is extended, each of said blocks supporting a roller 21.

For adjusting each block 20 a respective set screw 22 is provided, each screw being in threaded engagement with a respective lug 23, said lugs being borne by the plate 8.

The plate 9 is provided with a pair of oppositely disposed guideways 24 and slidably mounted within said guideways are a pair of blocks 25 each bearing a roller 26 and for adjusting said blocks are respective set screws 27, each having threaded engagement with respective lugs 28, which are borne by said plate 9.

The swaging tool 7 is provided with a bore 29 at its tapered end 30 and a counter-bore 31 at its opposite end, said bores 29 and 31 providing an interiorly formed shoulder 32, said swaging tool when mounted on the extension 6 of the mandrel 2 providing for the extending end of said extension to extend through the bore 29 and into the counter-bore 31, said swaging tool being loosely secured on the extension 6 by the nut 33 which bears against the shoulder 32.

In the operation of the improved attachment, a paper length 34 leading from a source of supply is spirally engaged unto the mandrel 2, then a paper length 35 is engaged on the mandrel spirally over the engaged portion of the paper length 34 as clearly shown in Fig. 1, the under face of the paper length 35 when overlapped on the paper length 34 will adhere to the spirally wrapped portion of the paper length 34.

The spiral winding of the paper lengths 34

110

and 35 upon the mandrel 2 is merely preliminary and it is required that it be done by hand and in which when portions of the paper length are wound into a tubular formation it is moved along the mandrel 2 in the direction of the arrow 36 towards the attachment 5 and at the same time that the spiral winding is being applied by hand the tubular formation thereof is fed under the wound portion 10 37 of an endless belt 38, said belt being mounted over pulleys 39 and 40.

A second endless belt 38^a having a portion 41 which is adapted to be wound around the mandrel 2 is mounted over pulleys 42 and 43:

15 After the paper lengths have been spirally wound along the mandrel 2 and beneath the portions 37 and 41 of the respective belts 38 and 38^a the belts 38 and 38^a are put into operation. This is brought about by power being 20 applied to the driving belt 44 and pulley 45 on which said belt is mounted, said pulley 45 being mounted on the shaft 46 which bears the pulley 43, and in as much as the pulley 42 is operated by the belt 38^a motion will be imparted to the shaft 47 on which said pulley 42 is mounted. A pulley 48 which is mounted on the shaft 47 will then transmit motion by the belt 49 which is mounted over the pulley 48 and pulley 50, said pulley 50 being mounted 25 30 on shaft 51 which bears the pulley 39. The pulley 39 will incidentally drive the belt 38.

On account of the acute angle in which the belts 38 and 38^a travel on and off the mandrel 2 and incidentally over the spiral winding of 35 paper lengths, the spiral winding designated as 52 will not only be turned upon the mandrel but will be moved forwardly along the mandrel in the direction of the arrow 36.

This turning and carrying forward movement of the spiral winding 52 will cause said spiral winding to feed itself on to the swaging tool 7, and inasmuch as the swaging tool 7 is loosely mounted on the extension 6 of the mandrel 2, the spiral winding or tube thereby 40 45 formed will cause said swaging tool to be revolved therewith.

It is to be noted that the swaging tool 7 is provided with opposing flat sided faces 53 and 54, said tool also being tapered at its forward 50 end as at 30, said tapered end providing for the newly formed tube to ride onto the swaging tool with ease by reason of the tapered end 30 being smaller in diameter than the mandrel 2.

55 As the tube which is originally made round in shape by the mandrel 2 which is in the form of a shaft is engaged over the flat sides 53 and 54, the pair of rollers 21 of the plate 8 will press against the portions of the tube that are 50 mounted over the respective flat sides 53, and as the tube is further travelled longitudinally over the swaging tool 7 the portions of the tool which are engaged over the respective faces 54 will be pressed against by the respective rollers 26 of the plate 9, said rollers 21

and 26 firmly pressing the tube into a square formation as shown more clearly in Figs. 2 and 3.

As the swaging tool 7 is revolved by the tube traveling longitudinally thereover, the engagement of the rollers 21 and 26 with the outer periphery of the tubing will cause the attachment 5 to be revolved within the collar 15 which is stationarily held and rigidly secured to the bracket 17.

75 From the foregoing description of this improved invention it is to be noted that the swaging tool 7 is practically a continuity of the mandrel 2 in which the tube is first formed circular on the mandrel and is changed to the form of a flat sided tubing as it is fed over the swaging tool 7.

The purpose of providing a flat sided or square tubing is so that square paper cans can be made.

80 85 What I claim is:

1. A tube making device comprising a mandrel, a swaging tool loosely secured to one end of said mandrel, said tool at its end which is adjacent said mandrel being smaller 90 in diameter than said mandrel.

2. An attachment for working on a tubular member comprising an outwardly bulging element over which the tubular member is forced, and adjustable pressing means for bearing against the tubular member as it is being operated on by said element.

3. An attachment for working on a tubular member comprising means for forming said member, means for longitudinally traveling said member, and an insertable reshaping element over which said member is longitudinally travelled turnably secured to one end of said forming means.

100 105 4. An attachment for working on a tubular member comprising means for forming said member, means for longitudinally traveling said member, an insertable reshaping element over which said member is longitudinally travelled, and adjustable pressing means for bearing against the tubular member as it is being operated on by said element.

5. A tube making device comprising a stationarily held mandrel, means for feeding and forming material around said mandrel, means for revolving and longitudinally traveling the formed material on said mandrel, said mandrel having a portion extending therefrom, and a swaging tool having a tapered end mounted on said extending portion and free to be revolved thereon, said tapered end of said tool being smaller in diameter than said mandrel and disposed adjacent the end of said mandrel.

110 115 120 125 6. A tube making device comprising a mandrel, means for feeding and forming material around said mandrel, said mandrel having a portion extended from one end, and other means turnably located on said extended portion of said mandrel adapted to receive 130

the formed material and reform said material.

7. A tube making device comprising a mandrel, means for feeding and forming material around said mandrel, said mandrel having a portion extended from one end, and a swaging tool loosely mounted on said extended portion of said mandrel for receiving the formed material from said mandrel, said tool adapted to reshape the material.

8. In a tube forming device, the combination of a stationarily held mandrel, means for feeding and forming material around said mandrel, means for revolving and longitudinally travelling the formed material on said mandrel, and a swaging member loosely secured to one end of said mandrel over which the formed material is forced, said member adapted to be freely revolved by the material being forced thereon.

9. In a tube forming device, the combination of a stationarily held mandrel, means for feeding and forming material around said mandrel, means for revolving and longitudinally travelling the formed material

on said mandrel, said mandrel having a portion extended from one end thereof, and a turnable swaging member mounted on said extended portion of said mandrel over which the formed material is forced.

10. An attachment for working on a tubular member comprising means for forming said member, means for longitudinally travelling said member, and an insertable reshaping element over which said member is longitudinally travelled turnably secured to one end of said forming means, one end of said element being smaller in diameter than said forming means.

11. A tube making device comprising a mandrel, means for feeding and forming material around said mandrel, said mandrel having a portion extended from one end, and a swaging tool loosely mounted on said extended portion of said mandrel for receiving the formed material from said mandrel, said tool having a portion which is smaller in diameter than said mandrel adapted to reshape the material.

CHARLES J. LOUIS.
